Application August 11, 1936, Serial No. 95,348

3 Claims. (Cl. 128—284)

Our present invention relates to improvement in absorbent pads and devices for holding the same in place on human bodies.

The principal objects of the present invention include the provision of a holder so constructed and designed as to afford adaptability thereof to bodies of different sizes; and the provision of absorbent pads especially designed and constructed for use with the holder to prevent leakage of 10 excretions at critical points.

More specifically stated, the invention resides in the provision of holders or wrappers adapted to enclose the lower portion of the body adjacent the crotch, and to hold the absorbent pads 15 in place; with cooperating fastening elements on the holder engageable to adjustably fit the holders to infants or persons of different sizes.

A further object of the invention is to provide on the holders and pads cooperating means to 20 maintain the pads in proper relation with respect to the holders and parts of the body to which they are fitted, and facilitating the removal and insertion of pads when required, without the use of extraneous fastening elements 25 such as pins.

As will become apparent during the course of the following detailed description of the accompanying drawings, the invention provides not only for the adaptability of the holders to bodies 30 of different sizes in such manner as to prevent leakage at the critical point, but also provides the utmost in comfort to the infants or persons on whom the holders and pads are used.

In the accompanying drawings we have illustrated preferred embodiments of our present invention, and

Fig. 1 is a plan view of a holder constructed in accordance with the invention with an absorbent pad constructed in accordance with the invention 10 applied thereto;

Fig. 2 is a plan view of an absorbent pad removed from the holder and partly broken away to show additional moisture absorbing elements incorporated in the pad;

Fig. 3 is a view taken on the line 3—3 of Fig. 2;

Fig. 4 is a perspective view showing the holder and pad of Fig. 1 inclosed position which it occupies when applied to the body; and

Fig. 5 is an enlarged sectional view taken on line 5—5 of Fig. 4.

In the drawings the holder is shown as composed of a relatively wide central back panel 6 to which relatively narrow side panels 7 are secured as by means of stitches 8. The panels 7 are relatively wide at their tops and taper to

narrow ends 9. The panel 6 has a depending elongated flap 10 located between the narrow ends 9 of the panels 7.

Obviously, the holder may be made from a single piece of material if desired, and the material used in forming the holder, whether it be made integral or as several parts as shown in the drawings, is a relatively light elastic material capable of withstanding the chemical actions of excretions to which it may be subjected.

The edges of the panels 6, 7, and flap 10 are bound by soft tape 11 which will not irritate the skin with which they come into contact.

The panels 7 are adapted to fold toward each other over the panel 6, and the flap 10 is adapted to fold upwardly over the panel 6 with its side edges located between the free edges of the panels 7. The curved or notched portion 12 at the juncture of the flap 10 and panel 6 is adapted to cooperate with the reduced or curved lower 20 ends 9 of the panel 7 to provide openings 13 (see Fig. 4) to accommodate the thighs or legs of wearer adjacent the crotch.

To provide for relatively unlimited and minute adjustment of the size of the openings 13 to receive thighs of different sizes, and to effectively prevent leakage, we preferably provide along the confronting or abutting edges of the flap 10 and panels 7, when in folded position, slide fasteners commonly known as "zippers" or their equivalent. Such fasteners are designated generally by the numeral 14, and as shown best in Fig. 5, the fasteners are carried by tapes 15 secured to the panels 7 by stitches 16. One of the panels 7 is provided with a relatively wide flap 17 which extends across the fastener 14 and preferable partially across the other panel 7. A similar relatively wide flap 18 is secured as by stitches 19 to the other panel 7 and tape 15 and extends also across the other side of the fasteners 14 and 40 tape 15. Thus when the device is closed, as shown in Fig. 4, the body of the wearer as well as outer garments are protected by the flaps 17 and 18, so that the fasteners 14 cannot contact the skin or body of the wearer. Of course the 45 flaps 17 and 18 are preferably made of soft material which will not irritate the skin of an infant.

From the description thus far given it should be apparent especially by reference to Figs. 1 and 4, that the holder is adapted for various uses 50 where absorbent material is to be held within and adjacent the crotch. However the invention is particularly, though not exclusively, adapted for use on infants. It should also be obvious that pads or inserts of various types of absorbent ma-

terial may be placed on the holder when in the position of Fig. 1 with a portion of the pad extending along the flap 10 and a substantial portion of the pad or insert disposed on the panel 6 so that when the infant is laid on the pad the flap 10 may be folded upwardly through the crotch and across the abdomen. The panels 7 may be folded inwardly toward the flap 10 after which the slide fasteners on the abutting edges 15 of the flap 10 and panel 7 are brought into interlocked relation to any desired extent to effect a snug but comfortable fit around the thighs of the infant to prevent leakage of excretions through the openings 13.

Another important feature of the invention is the provision of a specially designed and constructed absorbent pad or insert for use with the holders previously described. The pads have high absorbent quality, are soft, and therefore 20 comfortable, and are so designed as cooperate with the construction of the holders above described, to contribute to the prevention of leakage through the openings 13 around the thighs of the infant or wearer. Also, as previously mentioned, readily engageable and quickly detachable 25 interlocking means are provided on the pads and on the holder to facilitate insertion and removal of the pads, and to prevent appreciable relative movement between the pads of the holders.

Referring to Figs. 2 and 3, we have shown in detail a preferred form of absorbent pad attached for use in connection with the holder above described. This pad may be made of any suitable soft, highly absorbent material which does not irritate the skin. Materials from which highly absorbent pads are made are well known and any of the known materials may be made.

Referring to Fig. 2 the numeral 20 designates a relatively large panel of substantially the same shape and dimensions as the panel 6 of the holder so as to fit thereon. Extending from the panel 40 20 is an elongated relatively narrow panel 21 preferably formed integral with the panel 20 and of substantially the same shape as the flap 10 so as to fit thereon. The upper edge of the panel 45 20 is relatively thick as indicated by the bead or enlargement 22, and immediately beneath the bead 22 at opposite sides of the panel 20 are notches 23 which may be arcuate as shown, or 50 rectangular, wedge shaped etc., as desired to serve the purpose presently described. The sides of the panel 20 and panel 21 also have a bead or a thickened edge as indicated at 24, for the reason presently described. The lower end of the panel 55 21 is provided with a thickened edge or bead 25 similar to the bead or thickened edge 22, of panel 20. The beads or thick edges 22 and 25 afford reinforcement to the ends of the pad adjacent notches 23 and 26, the latter being provided adjacent the bead or thickened edge 24 of flap 21.

In Fig. 3, which is a cross section on the line 3—3 of Fig. 2, we have shown the beads or thickened edges 24 along the sides of the pad. The pad including beads 22, 24, and 25 may be made by superimposing a number of absorbent sheets, 65 preferably previously provided with the notches 23 and 26, and then pressing the sheets together by suitable dies to provide the central portion of thinner dimension than the edge portions. A mass of fibers or cellulosic material may be 70 molded to form pads such as shown in Figs. 1 and 2, instead of using separate sheets.

As previously pointed out, it is an important feature and object of the invention to prevent 75 the leakage of excretions through the openings

13 around the thighs of the infant or wearer; and also as previously pointed out the minute adjustability afforded by the slide fasteners contributes materially to the accomplishment of the leak-proof qualities of the pad and holder with 5 the attainment of maximum comfort. We have found that by making a pad with the thickened or beaded edges which coincide substantially with the panel 6 and flap 10, that this object of the invention is completely attained.

The upper portions of the beads or thickened edges 24 are located on opposite sides of the back and buttocks of the wearer, while the lower portions, that is, the portions disposed on flap 10 fit through the crotch and partly over the abdomen when the holder with pad attached thereto is applied as shown in Fig. 4. Thus the openings 13 around the thighs are surrounded at the critical point by the thickened or reinforced edges 24.

To maintain the pad such as shown in Fig. 2 in place on the holders to prevent relative movement, we may provide elastic bands or plain tapes or ribbons 27 across the panel 6 adjacent its top, and similar bands or tapes 28 across the flap 10; 25 the bands or tapes 27 and 28 being spaced apart relatively a distance substantially equal to that between the notches 23 and 26. Thus the pads may be slipped under the bands or tapes 27 and 28 so that the bands or tapes will engage in 30 notches 23 and 26 to maintain the pads in place on the holders. To apply the pads to the holders it is simply necessary to open the holders and insert the ends of the pads under the bands or tapes 27 until the relative position of Fig. 1 is 35 obtained, and, of course removal of the pads is easily accomplished by reverse operation.

An optional feature of the invention is the provision of additional absorbent material within the pads at the time of manufacture. To this 40 end a relatively heavy but flexible and absorbent sheet 30 may be disposed transversely across the panel 20 between the sheets or fibers from which the pad is made; and a similar sheet 31 may be disposed along the panel 21 partly overlapping 45 the sheet 30, so that at the critical point additional absorbent material is provided without discomfort to the wearer. We have found that the insertion of the sheets 30 and 31 in the manner shown and described in connection with Figs. 50 2 and 3 is desirable because it permits reduction of the amount of soft fibrous material forming the outer surfaces of the pad, and further provides against leakage of excretions on the critical point.

We wish to point out that pads embodying the features above described may be provided in various shapes and dimensions, for use in connection with holders of various shapes and dimensions; and that although the slide fasteners or "zippers" 60 have been found highly desirable because they permit of quick comfortable and effective adjustment, other means for effecting adjustability of the holders to infants or persons of different sizes may be used with the pads.

We claim:

1. A holder for absorbent pads to cover the crotch and regions adjacent thereto on the human body, comprising a relatively wide back portion adapted to enclose the region of the body 70 below the waistline at the back and sides and to overlie partially the abdomen at opposite sides thereof, a relatively narrow elongated flap on the lower end of the relatively wide back portion adapted to engage through the crotch and over- 75

lie the central portion of the abdomen with the respective side edges of said flap portion and said back portion disposed substantially in abutting relation on lines extending upwardly from the groins and converging inwardly across the abdomen, the side edges of said flap and of the relatively wide back portion being formed to provide curved leg openings at the bottom of the holder, and interengageable fastener means on said abutting side edges extending from said leg openings upwardly to the waistline, a fastener operator member slideable longitudinally along said abutting edges for engaging and disengaging said interengageable fastener members of the respective edges to close the holder about the body and means for locking the fastener operator member in any position of adjustment along said abutting edges whereby to adjustably retain the holder around the thighs with a snug fit thereby preventing leakage of excretions.

2. In combination with the structure of claim 1, an absorbent pad within said holder said pad conforming substantially to the configuration of said holder so that at the thigh encircling region and crotch it is conformed snugly to the shape of said regions and crotch. 5

3. In combination with the structure of claim 1, an absorbent pad within said holder, said pad conforming substantially to the configuration of said holder so that at the thigh encircling region and crotch it is conformed snugly to the shape of said regions and crotch, and cooperative means carried by the pad and holder for restraining the pad against both longitudinal and lateral movement with respect to the holder, whereby to maintain correspondingly formed portions of 10 15 the pad and cover in proper relative position.
